MUSICAL INSTRUMENT

Melvin L. Severy, Los Angeles, Calif., assignor to
 The Vocalsevro Company, Los Angeles, Calif.,
 a corporation of Delaware

Original application July 15, 1931, Serial No.
 550,987. Divided and this application April 10,
 1934, Serial No. 719,948

20 Claims. (Cl. 84—349)

The present application is a division of application Serial No. 550,987 filed in my name July 15th, 1931, this divisional application being filed pursuant to official requirement.

5 This invention relates more particularly to a musical instrument having a plurality of tone qualities synthetically built up of suitably chosen and graded partials, each partial being produced in the air through the agency of a pulsated electromagnetic field including a movable member and a coacting magnetizable member adapted to vibrate a sonorous element. It is not, however, restricted to such use, since the requisite pulsations may be produced through revolving commutators and brushes co-acting therewith, such as disclosed in my Patents No. 1,733,630 and No. 1,914,173.

10 An important object of the invention is the production of a musical instrument of one or 20 more manuals, which is relatively cheap, compact, and durable, exceedingly powerful, exceptionally diversified as to tone, and of unusual artistic capabilities.

15 A further important object of the invention is the provision of multiplexed sonorous members, each such member capable of responding at its own proper pitch when any one of a plurality of manuals is played, thus cheapening, simplifying, and greatly reducing the size of, the instrument.

20 A still further object of the invention is the provision of resonant means for the various octaves of the scale, especially adapted to the pitch and volume suited to that particular musical area of the instrument's gamut.

25 Another object of the invention is the production of an instrument, comparable in facility to the great organ, which shall possess throughout a true tonality not only as to its primes but as to all its partials, each and every partial being separately produced under conditions particularly adapted to its own needs, and never sounding outside those conditions.

30 Still another object is the production of an instrument which, size for size, shall enormously excel the organ in volume, and which shall have as many tonal colors with greater facilities in their use, while possessing only a very small fraction of the parts necessary in organ practice. Furthermore, the instrument herein disclosed is not sensitive to changes in temperature, and is free from tuning needs, up-keep difficulties, sluggishness of speech, impurities of tone, and inability to produce true soft tones.

35 In addition to the broader features of my invention there are special details of design and

of structure, assembly, and co-action of parts which will be hereinafter explained.

An important object of my invention is to provide sensibly simple or fundamental tones having for each manual employed, the eighty-four 5 pitches associated with a seven-octave scale tuned in equal temperament. Where cheapness and compactness are vital factors, these same eighty-four notes may also be used, not only for the pitch-giving primes of all the tones of the instrument, but also, suitably proportioned as to 10 loudness, for all of the other partials contained in its many varied qualities or timbres. This is what I denominate by "borrowing system", and is disclosed in my Patent No. 1,899,884 dated February 28, 1933. It is used in the present case because of its extreme simplicity and cheapness of 15 construction, coupled with a musical efficiency remarkable in so inexpensive an instrument. It should be understood, however, that in more elaborate instruments I prefer to use a non-borrowing system wherein the sounders used as primes are not at the same time used as upper partials, 20 since this affords an even greater musical excellence albeit it is relatively more expensive and 25 complex.

In musical instruments making use of a scale tuned in equal temperament, and depending for the musical pitches of such scale upon rotating members producing pulsations, all such pulsations, including those representing the well-known incommensurate ratios subsisting between certain notes of each octave, can be secured with an accuracy sufficient for all practical purposes by the employment of rotating members having but 30 six different rotative speeds for an instrument of a range of seven octaves. More rotative speeds may be used, and in some cases twelve have been used, but for simplicity and cheapness, the smallest feasible number of speeds of rotation is preferred. For this reason use is here made of the 35 general plan set forth in Patent No. 1,899,884, it being understood that where, in this present application, more than six moving members are shown, there are still but six rotative speeds, some 40 of said speeds representing the velocities of a plurality of moving members. These moving members or rotors carry pulsation-producing toothed annuli, and are driven and governed in a manner essentially like that set forth in said 45 Patent No. 1,899,884.

In the drawings:

Fig. 1 is a diagrammatic plan view of the driving and governing means for a three manual instrument, the three lowest octaves of each 55

manual being served by three differently-speeded rotors, each of the rotors serving any manual revolving at the identical speed of the equivalent rotor associated with the other two manuals;

5 Fig. 2 is a side elevation, illustrating the grouping of the pipes about a rotor serving some of the lower notes of the instrument;

10 Fig. 3 is a diagrammatic plan view of one of the three treble rotors of the instrument, illustrating the general scheme of arrangement or grouping of some of its sounders;

15 Fig. 4 is an elevation, illustrating the same plan of grouping about the central rotor;

20 Fig. 5 is a sectional view of certain details of a sounder particularly adapted to the lowest octave of the instrument;

25 Figs. 6 and 7 are respectively, a plan view broken away, and a side view, of a multiplexed sounder especially adapted to serve throughout the range of the second octave of the instrument;

30 Figs. 8 and 8^a are respectively side and plan views of a sounder intended to serve the third and fourth octaves of the instrument's range, that is, to and including note No. 49, only those parts necessary to a clear understanding of the device being shown in Fig. 8;

35 Fig. 9 is a side view of a sounder and its resonator, especially well fitted to serve for the next octave of the instrument, that is, notes No. 50 to 61 inclusive;

40 Fig. 10 is a sectional side view of a sounder suited for the next to the last octave of the instrument's gamut;

45 Fig. 11 is a side view of a sounder suited to the highest octave of the instrument;

50 Fig. 12 is a side view of a key of the manual, illustrating the key-contact systems used in an instrument having a plurality of manuals;

55 Fig. 13 is a diagrammatic illustration of the wiring system associated with one of the manuals, including also the tremolo mechanism;

60 Fig. 14 is an elevation showing details of a three-manual tremolo commutator;

65 Fig. 15 is a diagrammatic view of a wiring scheme adapted to a three-manual instrument.

70 Fig. 1 illustrates diagrammatically the placement of the rotors and the driving and governing mechanism for a three-manual instrument. It will be noted that the rotors serving the three lower octaves of the instrument are nine in number, the rotors for the groups of sonorous bodies indicated by the large numerals 1, 2, and 3, serving, respectively, in these three lower octaves all the notes C, C[#], D and D[#]; all the notes E, F, F[#] and G; and all the notes G[#], A, A[#] and B associated with one manual of the instrument, as, for example, the second or middle manual. Similarly, the rotors for the groups of sonorous bodies indicated by the large numerals 4, 5, and 6 serve respectively, the same notes of the three lower octaves of another manual, as for example, the upper manual; while the rotors for the groups of sonorous bodies indicated by the large numerals 7, 8, and 9 similarly serve, respectively, the same notes of the remaining manual of the instrument.

75 Instruments of this type are conveniently divided into operative and speaking sections, and Fig. 1 is mainly concerned with the speaking part of the instrument. As the driving mechanism shown in this figure is clearly set forth and described in my Patent No. 1,899,884 above mentioned, and the governing mechanism is described and claimed in my Patent No. 1,911,326

dated May 30, 1933, only brief treatment of them is necessary here. A motor 10 drives the belt pulley 11 through the agency of geared mechanism provided with a variable slippage factor consisting of a copper annulus 12 capable of retardation by the inductive action of the braking magnets 13, 14, the one constant and the other intermittent, the intermittent magnet being controlled by a centrifugal contact finger 15, and relay 16 and associated parts.

10 From the under side of the pulley 11 a belt 17 passes about the large pulley 18, thence under the adjustable, belt-tensioning idler 19 and about the large pulley 20. From the pulley 20 said belt 17 passes to the larger pulley 21, from which it 15 passes about the pulley 22, thence about the angularly placed idler 23 and back to the upper side of pulley 11, thus completing its circuit. This arrangement serves to give correctly timed rotation to the three rotors driven by the pulleys 20, 21, and 22, said rotors not being shown in Fig. 1. These rotors serve the four upper octaves of the instrument throughout its three manuals, for since the sounders for the higher pitches are so much smaller than those for the bass octaves, it 25 is convenient to place about each of the three high speed rotors all of the sounders associated with that rotative speed which are used in the threeproduced scale of a three manual instrument. In the three lower octaves, with their very much 30 larger sounders, a similar grouping about three rotors is not convenient unless the largest sounders at least, are multiplexed, and in Fig. 1, for clearer showing, I have preferred to show a separate sounder for each of the three notes C, 35 each of the three notes C[#], and so on throughout the lower three octaves of the instrument.

40 It should be understood, however, that where cheapness and compactness are sufficiently controlling factors, both may be obtained by the 40 employment for the instrument's lowest notes of the multiplexed sounders therefor which will be described later. The lay-out shown in Fig. 1 therefore comprises nine rotors for the three 45 lower octaves of a three manual instrument, while the four upper octaves thereof are served throughout the three manuals by the employment of three rotors only. The three rotative speeds of the nine bass rotors shown are one-fourth those of the corresponding treble rotors, and as clearly set forth in my Patent No. 1,899,884, each rotor bears pulsation-producing annuli adapted to generate at each revolution, sixteen, seventeen, eighteen, nineteen, or twice, 50 four, or eight times such numbers of pulsations, thus producing, with the six rotative speeds, all the vibrational frequencies of seven octaves of 55 a scale tuned in equal temperament.

60 In order to get the slower speeds necessary for the three lower octaves, a belt 24 passes from a pulley 25 to the rotor pulley 26 in the upper row of rotor pulleys, thence about an idler 27 and leftward to an adjustable, belt-tensioning idler 28. From the under side of idler 28 belt 24 passes 65 about the pulley 29 of the rotor for group 5 in the middle of said upper row, and thence to the top of pulley 30 of the rotor for group 8 of said upper row. The belt 24 then passes to the pulley 31 of the rotor for group 7 in the middle row, from 70 which it passes to the pulley 32 of the rotor for group 9 in the lower row; thence to the pulley 33 of the rotor for group 4 in the middle row; thence to the pulley 34 of the rotor for group 6 of the lower row; thence to the pulley for the 75

rotor of group 1; and thence to pulley 35 of the rotor for group 3 of the lower row, from the bottom of which it passes to the bottom of the small pulley 25, thus completing its circuit.

5 The resonant tubes of the sounders associated with the rotor of group 1 are indicated at 36, 37, 38, 39, 40, 41, 42 and 43. It is to be understood, however, that this showing could just as well represent either of the other two groups in this mid-
10 die row, since they are all identical, merely serving identical notes of different manuals. Four electromagnets 44, 45, 46 and 47 are associated with sounders 36, 38, 40 and 42, the electromagnets associated with the other four sounders being shown as broken away. The cores of said magnets project into close proximity to pulsation-producing annuli 48 carried by the shaft 49, one of which is shown but without teeth or wave forms owing to the smallness of its size and 20 the fact that all these details are so clearly set forth in the patents before mentioned. They will also be briefly referred to again in connection with Figs. 3 and 7 hereof. A belt 50 extends from the pulley 25 to the tremolo-actuating pulley 51, 25 more clearly shown in Figs. 13 and 14.

As set forth in said Patent No. 1,899,884, the sizes of the pulleys are so planned with reference to the driving speed that the shafts carrying the lowest notes C of the instrument shall rotate at 30 121.25 R. P. M. (see group 4), while the shaft carrying the highest notes C shall rotate at four times that speed or 485 R. P. M. The bass shafts carrying the notes E rotate at 152.7654 R. P. M. (see group 5), and the treble shaft carrying the 35 notes E rotates at 611.0617, while the bass shafts carrying the notes G $\sharp$ rotate at 192.4723 R. P. M. (see group 3), and the treble shaft carrying the notes G $\sharp$ rotates at 768.8895 R. P. M.

In Fig. 2 the rotor or shaft 49 associated with 40 group 1 of the sounders is shown in dotted lines, the pulsation-producing annuli 48 carried by said rotor being also shown in dotted lines throughout most of its length. The electromagnets 45, 47 are likewise shown in dotted lines with 45 their cores opposing some of the lower annuli on rotor 49. As shown in this figure, the resonant tube or sounder 36, as indicated by the numeral 1 preceded by the letter "N", is designed to give forth note number 1; sounder 37, note number 14; sounder 38, note number 3; sounder 42, note number 2; and sounder 43, note number 13. Shorter resonant tubes 52, 53, associated with notes number 25 and number 26, that is, note C of 129.33 vibrations per second and C $\sharp$ of 137.02 vibrations 50 per second, are likewise seen in this figure. The rotor 49 turns at 121.25 R. P. M., and carries all the notes C, C $\sharp$, D and D $\sharp$ of the three lower octaves of the instrument commanded by one manual of the keyboard. The two other rotors 55 associated with the same vibrational frequencies of the two other manuals of the instrument are identical with this and turn at the same speed. These three rotors of the middle row of the bass 60 are so essentially like those of the other two rows serving the higher letters of the musical octave throughout the bass section of the three manuals, that no further consideration of them is deemed necessary. The resonant tubes are somewhat shorter and, as will be observed in Fig. 1, 65 somewhat smaller of diameter as the pitches rise. The resonant tubes 39, 40 and 41 of group 1 are associated respectively with note number 16, note number 4 and note number 15.

Figs. 3 and 4 illustrate in diagrammatic plan 70 and in elevation, respectively, the grouping of

the sounders about the treble rotor 54 revolving at 611.0617 R. P. M., said rotor carrying all the notes E, F, F $\sharp$ and G of the four upper octaves of the three manuals of the instrument, each note number shown in the drawing appearing 5 three times, or once for each manual of the instrument. This is made possible without resort to multiplexing sounders by reason of the fact that the higher pitches of the last four octaves can properly be served by much smaller resonant 10 members. An annulus 55 with a small portion of its periphery dentated to illustrate the method of its co-action with the dentated head of the core 56 serving note 41, is illustrated in Fig. 3. It is to be understood that the wave-forms or 15 dentition of the annuli may be of any desired conformation, and may well vary even in the one instrument as between different sections thereof. To avoid annuli of undesirably large diameter and of objectionably high speeds of rotation 20 where compactness is a vital consideration, it has been found desirable to use a "wave-form" so-called, having active portions or "teeth" somewhat resembling those of gears, but preferably with spaces between them occupying much 25 greater peripheral extent than is occupied by the "teeth" or active portions themselves. It is also advantageous to curve or "let off" the peripheries of the "teeth" upon an arc of less radius than that of the annulus, all as set forth in the patent 30 mentioned. Where a tonal result characterized by sine-wave type of vibration is desired, I find it convenient where space and size are to be minimized, still to retain the gear-like type of active "tooth", rounded as mentioned, 35 and further to modify the result by the flexibly elastic member 57 or some equivalent, as will be shown in later figures hereof; by weighting to round somewhat the "take-hold" and "let-go"; and by the use, in most instances, of resonators 40 as shown herein. In this manner sensibly sine-wave simple tones are secured through the agency of annuli of practicable size even where an annulus carries several scores of "teeth" or "wave-forms". It is distinctly to be understood, 45 therefore, that I do not confine myself to any particular shape of dentition or wave-form of the annuli, as that may be varied to suit conditions as aforesaid.

In Fig. 3 notes numbered 41, 42, 43, and 44 are 50 thrice exhibited, once for each manual of the instrument, their tubular resonators 58 extending upward as shown in elevation in Fig. 4. Below these notes are seen at 59 the radially outward ends of the shorter and different type of resonators used for the thrice exhibited notes marked on the drawings N-53, N-54, N-55, and N-56. It will of course be understood that this rotor 54 serves notes not possible to show clearly in the 55 drawings, each treble rotor of a three manual instrument of this type caring for sixteen notes thrice represented, or forty-eight in all. The housings 60 for the electromagnetic solenoids are indicated in dotted lines, the flexible support 57 60 for the radially outward end of a core carrying the plunger 57^a co-acting with the opposed resonator being likewise shown in dotted lines. These members may be supported in any suitable manner, no such supports being here illustrated 65 since it would unnecessarily complicate the showing of this figure. In Fig. 4 the annuli 55 are shown partly in dotted lines, all of said annuli in this figure being without wave forms or dentition. 70

Fig. 5 illustrates a resonant tube 61 suitable for use in connection with the lowest bass of the instrument. This resonator, where compactness is a considerable factor, may be multiplexed in the same manner as the sounders illustrated in Figs. 6 and 7. It is desirable that the lowest notes of an instrument shall have not only very great volume, but also that they shall be capable of marked loudness of utterance, and this construction is directed to this feature. A diaphragm 62 of plunger type is suitably stiffened by ribs 63, and is elastically held in the casting 64 by an annulus or disk 65 of leather or other suitable material, securely clamped to said casting by an annulus 68 screwed thereto. The flexibly elastic members 67, 68 which carry the plunger 62 are shown broken away, and their functions will be fully described in connection with Figs. 6 and 7. It will be noted that the casting 64 forms as it were a perforated floor for the pipe 61, the upper side of the floor being flat and in a horizontal plane, while the under surface with its opening 61a presents the conformation of the frustum of an extremely obtuse cone, the purpose being to make as efficient a pumping mechanism as possible. The ribbed and leather-hung plunger 62 swinging upon the members 67, 68, and two other similar members not appearing in this figure, moves not as an ordinary diaphragm having its maximum motion in the center, but rather as a plunger with an equally wide movement throughout its area, thus producing a very great effect upon the air. The perforated floor 61a is shaped and placed so as to permit the most perfect evacuation of air feasible upon the up-stroke, the slant of its lower side serving to prevent any choking action as the air from the outside area is forced into the smaller superficial area near the opening. This results in a pronounced amplification of action and increase of loudness, a most desirable attainment in the case of the lower notes of the instrument, say from numbers 1 to 18 inclusive.

Referring now to Figs. 6 and 7 which show the same structure, the rotor 49 for group 1 of the bass sounders and an annulus 48 carried by the same are here illustrated, a portion of said annulus being dentated as shown opposite the dentated portion 69 of the co-acting core. As shown in my patents before mentioned, and as indicated in connection with the description of Fig. 3 hereof, wave-forms or tooth-like dentitions of any desired shape may be employed according to the special exigencies of the case. The resonant pipe 61, plunger 62, and ribs 63 are also seen in Fig. 7. Bent metallic springs 67, 68, 70, and 71, broadest at the ends fastened to the pipe-supporting casting 64 and tapering toward their opposite ends, are secured in a somewhat interleaved fashion to the central stud 74, this construction assuring the to-and-fro motion of plunger 62. To the inner end of stud 74 and within the tube, a variable weight 75, shown in dotted lines in Fig. 7, serves to bring the whole system somewhere near resonance as well as to soften, as aforesaid, the sharpness of the pluck of the energized core when traversed by the teeth of an annulus leaning in type toward those of a gear. This weight 75 may be placed at any convenient part of the system, but, where room permits, it is well to have it intimately associated with the plunger, either inside or out.

A magnet rail 76 normally carrying three sole-

noidal magnets 77, the central magnet being omitted in Fig. 6 but shown in section in Fig. 7, is supported at 78 as indicated by dotted lines in Fig. 7, the supports 78 being secured to the further side of the tube-supporting casting by screws 5 79. In Fig. 6 both the magnet-rail 76 and the rotor 49 are broken away better to show the structure and action of a pivoted arm 80 upon the outermost bent metallic spring 70, said arm being secured to said spring 70 at 81 by a link 10 82, the leverages being so planned that a given movement of its associated core shall give plunger 62 exactly the same traverse as will be given it by the same movement of either of the other cores acting upon it. This pivoted arm 80 rocks 15 at 83 between bearings 84 of the casting 85 secured at 86 to a boss 87 integral with the tube-supporting casting 64. The ring or annulus 66 securely screwed to the main casting with the plunger-supporting leather gasket 65 between it 20 and said casting, is likewise shown in Fig. 7. A trunnioned member 89 rocks about a pivot 90, the threaded inner end of core 91 passing freely through this member, but being prevented from reciprocation by the lock-nuts 92 which serve to 25 adjust the core nearer to or farther from its associated annulus for purposes of voicing. Spiders 93 having corrugated arms elastically support the dentated or rotor-end 69 of the cores 91 so that they may reciprocate freely without 30 contacting their surrounding solenoidal tubes. Disks 94 (Fig. 6) which may well be of aluminum or brass, serve to cover the chambered portions of the magnet-rail occupied by the magnets, the free space 95 (Fig. 7) being usually filled with 35 plaster of Paris or some suitable substance serving both to hold the bobbin rigidly and better to connect it thermally with the rest of the rail while electrically insulating it therefrom. This promotes cooling and keeps the solenoids more 40 efficient, a method of procedure clearly shown in Fig. 10. Washers 96 are placed beneath the radially outermost ends of the spider-arms 93, through which and the disks 94 the spider arms 45 are secured to the magnet-rail, their inner ends being securely fastened to and beneath the expanded core head as clearly shown in Fig. 7.

The parts omitted from Fig. 5 are identical with the corresponding parts of Figs. 6 and 7, but it will be noted that in Figs. 6 and 7 the resonant 50 tube has no perforated floor but is stopped by the bodily-moving plunger 62, so that any amplification of the tone in this instance is due to the fact that the leverages are so planned that the plunger 62, as shown, moves about two and 55 a half times the distance traversed by the cores associated with it.

Referring to the two spidered cores 91 shown in Fig. 6, it will be seen that the ends of the cores farthest removed from the co-acting annuli reach the flexibly elastic tapered members with which they are associated, and to which they are fastened, at a point to yield about the aforesaid magnification of movement, while the doubly compounded motion of the system associated with the arm 80 is such as to produce the same enlargement. The annulus 48 of Fig. 6, while the nearest to the observer of all the objects of the figure, is shown in dotted lines to avoid obscuring important members beneath it. The plunger-carrying annulus 65 of leather, rubber, or other suitable material is also seen in Fig. 6.

The type of sounder seen in Figs. 6 and 7 is that which I find suitable for a range of the bass of the 75

instrument extending from about note number 14 to note number 25 inclusive, and the pipe being multiplexed as shown, it may well be of large diameter and of great volume.

5 It will be seen from Figs. 5, 6, and 7 that while there are four elastically flexible, tapered, plunger-carrying members 67, 68, 70, and 71, only three of them are energized by magnets when the greatest possible power is demanded. This four-support system, however, brings the active arms in better relation to the rotor than would a three-arm system. The three magnets as shown are in line, though the center one is omitted in Fig. 6, better to show what lies beneath it. The 10 resonators associated with notes numbers 26 and above, are of a size which will ordinarily permit the grouping of three of each note number, one for each manual, about their respective rotors, even where different manuals are not served in 15 the bass by different rotors, as illustrated in Fig. 1 merely for the sake of clearness of showing.

The operation of the multiplexed pipes shown in Figs. 6 and 7 is as follows:

The three bent metallic springs 67, 68, and 70 are capable of energization by the magnets whose cores are attached to them either directly or through the pivoted arm 80, and the inner ends of all four bent metallic springs are connected to the central stud 74 of the plunger forming the 20 reciprocating floor of the resonator tube. When, therefore, the pressure of a key of a manual, as for instance, key number 13 of the first manual, acts through the operative system to energize its associated magnet, the result will be that the co-acting core will be attracted and released by the alternate passage of relatively near and relatively remote portions of the revolving annulus opposing it. These motions will be transmitted through the associated bent, metallic spring to the plunger 25 floor of the resonant tube, thus causing said tube to emit its proper note with an amount of loudness proportional to the amount of current flowing in the energizing coil about the active magnet-core. If at the same time, the same note, 30 number 13, of either or both the other manuals be pressed, care having been taken that the centers of the teeth of all cores thus associated in the multiplexing of a sounder shall simultaneously pass the centers of the teeth of their co-acting annuli, the associated core or cores will be energized proportionally to the current flowing 35 about them. The associated bent metallic spring or springs will then transmit the energy to the plunger, the result being that the plunger will make longer excursions the more power it receives.

As the energizing solenoidal magnets of a multiplexed pipe are each upon a circuit controlled by a separate manual, it will be seen that a pipe so multiplexed may perform all the functions of three pipes speaking at the one pitch and controlled by three separate manuals, for the sounding of a pipe through pressure of a key of one manual is no bar to any desired simultaneous sounding of the same pipe in response to pressure of the corresponding key of another manual.

Considering now Figs. 8 and 8a, which are two views of the same structure, Fig. 8a showing only such parts as are necessary to a full interpretation of Fig. 8, the housing 72 for the solenoidal magnet 77 (shown in dotted lines), is provided with a flange seen at 72a. The metallic C-spring 97 is screwed to this flange, and to the free end 75 of said spring is fastened the casting 98 carrying

at the rightward end the ribbed circular plunger 62 adapted to beat air into the resonant tube 61. This plunger is secured to the casting 98 by a threaded stud 99 carrying weighting washers 100 of lead or other material, secured between two nuts 101. It is to be understood that while a system of vibration which is more or less "forced" requires nothing for its mechanical movement in the way of weighting or tensioning which would satisfy the exacting needs of musical tuning, yet, notwithstanding this rather wide workable latitude, the nearer true resonance is reached in a system, the greater will be its efficiency and the less "forcing" it will need, a fact which explains one important reason for using weights and proportioning the springs to the work in hand. The resonator tube 61, while it will respond throughout a rather wide range from the standpoint of tuning accuracy, should be proportioned with care to the pitch of the note it produces, in order that its utterance may be sensibly perfect. This system of tone production must not be confused with organ practice where the pitch as well as the quality of the tone is determined by the pipe, for here the pitch is determined outside the pipe, and the quality is made in an entirely new manner. If the resonator does not suit the pitch delivered to it, it will have to be "forced", and will speak less and less efficiently the more it has to be "forced".

A screw 88 (Fig. 8) is threaded into the lower end of core 91, which is slit for a little more than the distance of the thread in order to prevent possible rattling. This screw 88 passes freely through the swinging member 102 which is pivoted upon threaded centers formed on the screw 103 adjustably and securely held in the casting 98 by the check-nuts 104. A threaded thumb-wheel 105 together with a nut 106, serves to position and secure the screw 88 relative to the swinging member 102 and the casting 98, thus serving to adjust the core 91 with regard to its co-acting annulus (not shown in Figs. 8 and 8a).

It will be noted that the casting 98 serves both as an amplifying extension for the C-spring 97, and as the major part of the weight necessary to ease off the attack and let-go where a gear-like form of annulus-tooth is used and an approximately sine-wave form of result desired at the plunger 62. Where this is secured the resonator will do the rest, delivering a full and beautifully formed simple tone. This type of sounder, with its relatively large resonator and considerable amplification, is well suited to meet the requirements of the highest of the three bass octaves of the instrument, as well as the lowest of the four treble octaves, covering in all notes No. 26 to No. 49 inclusive, the plunger and resonator sizes being progressively diminished as the pitches rise.

In Fig. 9, 72 indicates the housing of the solenoid; 91 the core which as seen at 69, has five dentitions or "wave-forms" where Fig. 8 shows but three, while Fig. 11 shows six, the explanation being that, as the pitch of notes rises, the "wave-forms" or teeth are more numerous and nearer together, thus permitting more teeth within the normal space of an enlarged magnet-head. The spiders 93 shown and described in connection with Figs. 6 and 7, and seen also in Fig. 8, are likewise illustrated in Fig. 9. A bent metallic spring 108, preferably of soft steel that it may not retain magnetism, yet may afford a good path for the return lines of force, is secured at its ends 75

to the longitudinally-extended flange 72^a of housing 72, the mid-portion of said spring being secured to the lower end of core 91 which passes through the riveted portion 109, and into the 5 central stud of the ribbed plunger 62. An adjustable weight 110 is attached to the core for purposes already clearly set forth. A resonator 61 is shown broken away, to indicate that it may be of any desired length suitable to the different 10 notes served by the various sounders of this type, which type I find well adapted to notes numbered 50 to 61 inclusive. The spring 108 is held at both ends, thus making it somewhat less resilient and better suited to vibrations ranging from 548.07 to 15 1034.61 per second. The notes being of relatively high pitch, do not require a loudness which necessitates mechanical amplification.

Referring now to Fig. 10, the housing 72 for the solenoidal magnet 77 is shown as embedded in 20 an insulating material 95, as previously mentioned in connection with Fig. 7. The core 91, spider 93, and associated parts are also illustrated in Fig. 10, the core head 69 in this instance carrying five narrow teeth intended to oppose an 25 annulus with the considerable number of teeth necessary for so high a pitch as this type of sounder is designed to serve. The flange 72^a of housing 72 is circular in plan, and is adapted to receive the circular and annularly and concentrically grooved member 111 which is firmly clamped, diaphragm-wise, between said flange 72^a and the metal retaining ring 73, which may 30 be of lead so that it may damp the peripheral vibration of the grooved member, concentrating 35 the same, as much as possible, at the thickened innermost area carrying at its center the reduced and threaded end 112 of the magnet core. Metallic washers 113 permit the nut 114 to bind the said innermost area firmly between itself and 40 the shoulder of the magnet core. 115 indicates disk laminæ used for weighting, and secured to the core end 112 by a nut 116. The grooved member 111 may be of any suitable material, but I have found a good grade of maple to serve 45 excellently where a simple fundamental tone is desired, as in this case, for even were there faint upper partials, they would be so evanescent as not to be objectionable where wood is used. To ensure the necessary fundamental quality, the 50 member 111 is left thick at its center that it may vibrate as a plunger, rather than breaking up as a diaphragm might do. This type of sounder is excellent for notes extending from No. 62 to No. 55 73 inclusive. As these pitches are so high, resonators may ordinarily be entirely dispensed with, the area of the vibrating member 111 furnishing volume quite sufficient for tones which are so incisive.

Fig. 11 shows a construction similar to that of 60 Fig. 10, the magnet flange 72^a being entirely circular in plan but much smaller, and a relatively short, six-toothed magnet core 91 suitable to the highest pitches of the instrument being illustrated. The lower end of this core is shouldered 65 and thrust through a diaphragm 117, to which it is securely attached by the nut 118, the weighting laminæ 115 and securing nut 116 being also shown. The diaphragm 117 is of any suitable material, a ring 119 which may well be of metal as 70 soft iron, being provided to facilitate return lines of force. Screws 120 clamp diaphragm 117 in place. By making the diaphragm of soft steel the resistance of the magnetic circuit will be greatly lessened, permanent magnetization being 75 avoided, while any upper partials that might be

present are so high in pitch as to cause no inconvenience whatever. This type of sounder is designed for the highest octave of the instrument, that is, from notes No. 74 to No. 84. These pitches, the lowest of which represents 2,192.26 5 vibrations per second, are so acute as to require a relatively small volume to enable them musically to balance the lowest notes of the instrument, so that the diaphragm of small diameter is of sufficient area, due reference being had to the 10 scale used in the drawings which, in the case of Fig. 11 is approximately one-half size, though I do not of course, limit myself to particular sizes, actual or relative.

Fig. 12 illustrates a slightly modified form of 15 the key-action shown in my Patent No. 1,899,884 and described in detail therein. The key-bed 121 is provided with longitudinally extending raised portions 122, 123, from which pins 124, 125 extend upwardly and serve to position or space the 20 keys with regard to each other, in the well-known manner. The essential difference between this figure and the construction of my Patent No. 1,899,884, just referred to, is the additional multi-contact block and its associated parts, made necessary because of the plurality of manuals used with the present instrument. A white key of the manual is indicated at 126, the felted key-strip 126^a limiting the upward movement of the keys under the urgency of spring 127. A projection 25 having a screw-eye passed through it, and an adjusting leather nut, are provided at the rear of each key for the purpose of tensioning spring 127, the lower end of said spring being looped about a slanting notched dowel 127^a glued into the rear 30 of the key-bed.

Tongue springs 128, 129 are screwed to said key, these springs being regulated as to their degree of depression by the adjustable screws 130, the shouldered lower ends of said screws passing 40 through the key as shown. Multi-contact blocks 131 are screwed to the key-bed beneath each key, each block being grooved to fit over longitudinally extending positioning strips 132, 132^a, which serve to keep pressed upward in passive position 45 the wire tongues 133 serving as contact members. Current is supplied by cables 135 to the wires passing through the wiring strips 134. A continuous metal strip 134^a serves as a common lead or return, as the case may be, since it is immaterial which purpose it serves if other conditions are suitably adjusted. The contact wires from tongues 133 are bent upwardly at their right-hand ends to facilitate wiring into the cables 135 or onto the continuous strip 134^a. One similarly disposed wire of each block 131 is joined to 50 said strip as seen in Fig. 12, the connection being parted to avoid confusion in the drawing and the open ends thereof being indicated at 134^b, 60 134^c, respectively.

The tongue springs 128, 129, each carry at their lowermost ends a contacting strip 193, 194, preferably of silver, long enough, transversely to the keys, to bridge safely all of the associated contacts 133 lying beneath them, to the number of four in each case. Of these two systems of four contacts, one contact in each case serves as a common return as described in said Patent No. 1,899,884, the other three contacts in each case 65 being wired to the other sides of appropriate magnets in the operative system as later described. The essential point in connection with Fig. 12 is that in this instrument each of the keys of each of the manuals is provided with 70 75 80 85 90 95 100 105 110 115 120 125 130 135 140 145 150 155 160 eight contact-systems, two of which are used as returns.

Fig. 13 illustrates in its upper portion what is termed the "partial-mixing system", as applied to a single manual and its associated speaking magnets, each as shown and described in my Patent No. 1,899,884, but in this instance the tremolo system for a single manual has been added to render more easily understood the system applicable to a plurality of manuals as shown in Fig. 14. 136 (Fig. 13) indicates the speaking magnets, each of said magnets having associated with it the number of the note of the gamut which it controls. Thus the extreme left-hand magnet 136 in this figure controls note #11, the magnet to the right thereof, note #12, the next magnet to the right, note #13, and so on. Associated with each pair of magnets 136 is a resistance 138. The bar 137, assumed in this showing to be movable transversely of its length, affords means for positioning the contact tongues 138^a along the resistance coils 138, thus diagrammatically representing the electrical result attained by the various partial-rockers indicated at 139.

In the center of Fig. 13 are three vertical rows of block-like members with ten blocks in each row, placed wide apart to permit showing the wiring, the central row of said blocks being doubly tipped with silver so that the blocks may contact properly on both sides. The left-hand row of ten contacts in Fig. 13 is brought into electrical connection with the opposing co-acting surfaces of the central row of contacts when key #13 of the manual is pressed and the partial-rocker 139 representing the first partial is in operative position. Similarly, the right-hand row of ten contacts is brought into electrical connection with the opposing co-acting surfaces of the central row of contacts when key #14 of the manual is pressed. Since a seventh partial is omitted in this instrument as shown, a graded "sub-octave" taking its place, and because it is more orderly to start the moving contacts with the "sub", it will be noted that the first partial 45 is crowded up to the second moving contact in each row. It will be seen, therefore, that each speaking magnet 136 (which in shop practice is always designated by the number of the key of the manual normally causing it to speak when such key is pressed) is wired, as shown, from its nearer pole to the second contact of the associated side of a double relay bearing said manual note-number, such double relay bearing a number in accordance with the control of its two actuating magnets by two separate adjacent keys of the manual, as fully explained in my said Patent No. 1,899,884.

In order to make clearer the showing of Fig. 13, directions for the wiring of each contact have been noted opposite the outside contacts of the double relay. It will thus be seen that every such contact save only the second in each outside row, invariably sends a wire to an outside second contact of some other double relay, which is always treated with regard to its numbers in such wiring as if it were two single relays of adjacent numbers. To make it clear to which relay the second of each of these contacts is wired, the note number, which is to say the relay number, is indicated on the drawings, together with the letter of the octave representing the note and the number of vibrations normally elicited by the pressure of the similarly numbered key of the manual. For example, considering the left side

of the double relay in question, which is designated "relay #13", the contact marked "2" is for a prime or first partial having 64.663 vibrations per second, represented on the manual by the note C. The next contact marked "3", therefore, will be for the second partial which, being of twice the number of vibrations, represents the note C an octave higher having 129.326 vibrations per second, and associated with the twenty-fifth note of the manual. This third contact will accordingly be wired to the second moving contact of relay #25, the outside rows of contacts of a double relay being thus referred to as "moving". All of the other contacts of the outside rows are similarly wired, it being obvious that in the case of the double relay #15, #16, the numbers applying to relay #15 will be just one number higher than those applying to relay #14 in similar cases. The same procedure will apply to relay #16 so that the entire relay wiring of the instrument may be set down from a consideration of what obtains in the case of one relay, even though it were not a double one.

In the central row of contact tongues in Fig. 13 each of said tongues is to be understood as wired, though not so shown in the drawings, to two adjacent notes upon its associated partial-mixing rocker 139, after the manner clearly set forth in said Patent No. 1,899,884. For example, the tongue marked "Sub" in the drawings has a wire 140 leading to a rheostat 141 of the particular partial-rocker reserved for this "sub", forty-two wires 140 being provided for an eighty-four note instrument, as indicated in the drawings. From the central contact marked "5" a wire 142 leads to a rheostat 141, the other end of said resistance being connected to a contact tongue 143 serving upon the fifth partial rocker, the forty-first and forty-second notes of the manual. It will be observed that there is another fifth partial rocker 139' and another resistance 143' in parallel with the resistance 143 serving the partial rocker just described, and these two resistances may be of any desired ohmic value. If, therefore, the first described fifth partial-rocker be actuated, the loudness of the fifth partials will be determined by the ohmage of the resistances 143, while if rocker 139' is actuated, the resistances 143' will determine the loudness. If both these rockers be actuated together, still another loudness will result from the simultaneous use of the two resistances and the two rockers, as will readily be seen, three different loudnesses of the fifth partial with two rockers and their associated resistances being thus obtained.

This mechanism, by means of which any desired number of differences of loudness may be given to any partial, is fully described in my Patent No. 1,899,884, and is only set forth here to make the showing more complete.

The tremolo commutator-pulley 51 is suitably propelled as shown in Fig. 1, brushes 144, 145 bearing upon the commutator, which serves as elsewhere described, electrically to connect and disconnect the tips of said brushes alternately, so that when the tremolo knee-swell 146 is pressed rightwardly a resistance, inversely proportionate to the degree of the pressure, shall connect said brushes irrespective of the angular position of the commutator upon which their rightward ends rest. The result is that when section 147 of said commutator passes under the brushes they are short-circuited and the resistance of the line at

this point rendered negligible, while, when the commutator reaches the position shown in the figure, the resistance of such portion of the coil 148 as the movement of the knee-swell does not cut out, will be inserted into the line at this point. The knee-swell 146 is positively positioned against a stop 149 by a spring 150, which causes the bifurcated brush 151 having one prong somewhat longer than the other, to rest wholly upon insulation at the right-hand end of drum 152 carrying the coil 148, this coil being traversed by brush 151 when the knee-swell is operated. The pronged brush 151 is carried by a flat slideable bar 153 running in graphited felt bushings, said bar having secured to its leftward end a flexible wire connection 154. Another connecting wire 155 is secured to the leftward end of the helix or coil 148, this wire being suitably secured to the box containing the drum 152 by a binding post or equivalent means. A link 156 serves to connect bar 153 with the innermost extremity of the rod of knee-swell 146.

A flexible contact spring 157 is secured to the left end of the box which houses the resistance drum 152, the left end of helix 148 and of wire 155 being secured to this contact spring. To insure perfect and correctly timed contact, the contacting end of spring 157 is adjusted relative to its coacting contact by a screw 158 passed through an opening in the spring. An angularly bent member 159 is secured to the slideable bar 153, and pushes the flexible contact 157 slightly to the right as member 159 contacts with said tongue under the action of spring 150, thus shutting off the tremolo upon the removal of the player's knee, and cutting out the resistance helix irrespective of the position of the revolving tremolo commutator.

The alternate high and low resistance of the line at this point produces a "shake" or tremolo in the tone, more or less pronounced according to the position of the knee-swell. It is to be understood that in the three manual instrument forming the basis of this application, Fig. 13 applies to each of its manuals, except that the three tremolo commutators may well be on the same shaft and propelled by one pulley. This arrangement is illustrated in Fig. 14, where the manuals are indicated by the roman numerals I, II, III, and three pairs of brushes 144, 145 associated with the three commutators, are shown.

Fig. 15 illustrates diagrammatically the speaking magnets and their associated parts, as described in my Patent No. 1,899,884, rendered applicable to a three manual instrument. The speaking magnets 136 are associated with the first manual of the instrument, while the magnets 160 are associated with the operative system of the same manual. The magnets 136^a, 160^a are associated respectively with the speaking and operative systems of the second manual of the instrument, while the magnets 136^b and 160^b are associated with the speaking and operative systems of the third manual of the instrument. The common bars 137, resistances 138, contacts 138^a, and associated parts, serve to illustrate the action of the expression-control systems of the three manuals, these being but reduplications of that shown and clearly described in detail in said Patent No. 1,899,884. To avoid a confusion of wires, only the circuits of the speaking magnets are fully shown, those of the magnets of the operative systems being indicated by plus and minus signs. These magnets are those associated with the same four keys, as for example #13, #14, #15,

#16, of each of the three manuals, and as shown at 161 the speaking magnets are connected together in pairs on one side. Similarly, the central relay contact 162 of each relay serves for both members of its pair of associated speaking magnets, as clearly set forth in my aforesaid patent. Manual keys 163, 164 of each of the three manuals representing notes #13 and #14 are associated in a pair in each case as aforesaid. The pedal keys 165, 166 correspond to keys #13 and #14 of each of the three manuals when the instrument is "multiplexed" as shown here. The outside relay contacts 167, 168 are connected respectively to one side of speaking magnets 136, forming a pair. As shown in Fig. 13 the relay contacts 162, 167, 168 are but three of a contact system having for each relay thirty contacts, that is, three rows of contacts as shown, but ten deep in a direction not convenient to show in this view.

The electrical placement of the three tremolo systems is schematically shown at 169, 170, 171, each of said devices being essentially like that shown in Fig. 13 with slight modification as indicated in Fig. 14. The partial resistances 141 are more fully shown in Fig. 13, this figure being scarcely more than a multiplication of the system applicable to a single manual of the instrument, with the addition of keys for a pedal bass. 172 indicates a source of current and 173 a wire leading from the negative pole thereof. A wire 174 leads from the positive pole of said source and branches into three wires before entering the tremolo system. Positive wires 175, 176, 177 emerge from the tremolo system and pass respectively to the three common wires 178, 179, 180 of the three partial rocker systems serving the three manuals.

The operation of the system is as follows: Suppose key #13 of manual I be pressed, causing the contact point 181 to close with its co-acting contact 182, thus passing negative current to the relay magnet 160 marked "N 13", whose other pole is connected to the positive side of the electrical source of energy. This energizes magnet 160 of the operative system and causes the contact 167 associated therewith, in common with the nine others in the same row but not shown, to contact with the central row of contacts 162 of which only one (associated with this relay) appears in the drawings. Current then flows from source 172 through wire 173 to the expression-control member 138^b associated with the common bar 137 for manual I; thence through the resistance to the branching circuit at 161, whence wires lead to speaking magnets 136 associated respectively with notes #13 and #14 of the first manual. As only the contact block 167 associated with the upper magnet 136 is electrically co-acting with its associated central contact, from which the rest of the circuit via the partial resistance 141, contact member 183, common wire 178 and wire 175 back to source 172, is supplied, only the note associated with the speaking magnet for note #13 of the first manual sounds, which it does with a quality determined by the mixing system, and a loudness determined by the expression-control system. If, now, the pedal bass key 166 associated with note #13 of manual I be pressed, negative current flows from its across the contacts 184, 185, to the self-same magnet 160 of the operative system, the other pole of which is wired to the positive side of the source of current. This energizes said magnet 160, which then acts precisely as before and with the

same result. Fig. 13 embodies a schematic representation of a system based upon the use of the multiple relay shown in Fig. 22 of said Patent No. 1,899,884. It is obvious, of course, that the type 5 of relay shown at Fig. 20 of that application might be used, but for compactness and cheapness of construction I ordinarily prefer the multiple type herein indicated.

I wish to make it clear that in a powerful instrument of the kind herein set forth, a properly worked out scale dictates, if the best results are 10 to be attained, frequent changes in the type of sounder as the pitch of the notes served by the sounders rises, permitting the volume of the tones 15 to be decreased according to the well-known values subsisting between high and low tones. For this reason I have thought it expedient to illustrate these most desirable types, and to indicate the ranges of tone over which each may well 20 be used, though of course I do not limit myself to the specific types of sounders herein illustrated and described nor to the precise ranges given as the limits are naturally somewhat elastic, a few notes either way not being fatal, even if not giving 25 the most ideal results, and I consider these various sounders an integral part of my invention.

There is still another advantage of my system of tone-production too important to be overlooked. So far as I am aware all other keyed 30 instruments now in use are tuned in equal temperament as to their primes, and owe their timbres to these primes being associated with certain other partials which are not tuned in the same temperament and do not, therefore, produce 35 ideally smooth results. In my system, however, all the upper partials as well as the primes of all tonal qualities are in the one temperament, thus leading to a perfection of result not otherwise attainable. As every sounder used is planned for 40 service as a prime, and is only called upon to produce one simple tone at the one pitch, notwithstanding its use for upper partials in tones having primes below this pitch, it is possible for 45 the first time in keyed instruments, so far as I know, to produce tones of any conceivable composition, all of whose partials are perfectly formed, chosen, and graded entirely at will, and without those limitations which have heretofore 50 beset makers of musical instruments.

While the pulsation-producing members 48 are shown as annuli, and will preferably be made in 55 annular or ring form, it is obvious that they may be complete disks suitably separated from one another and permanently united to form an extended rotor.

I do not confine myself to the particular manner 60 of initiating tone herein shown, nor to this exact way of controlling tone color or timbre, since any means of producing a plurality of sets of repetitive impulses all in one temperament and of simple wave-form, selecting these sets as to order, grading them as to relative prominence, 65 and using them as all the components of compound tones of various timbre, I hold to be well within the scope of my invention, and I have elsewhere shown several other ways any of which, suitably designed, might be similarly used in the 70 broad combinations herein claimed.

No claim is herein made to the multiplexed instrument per se, the same being reserved for and 75 claimed in my said application Serial No. 550,987, filed July 15, 1931.

What is claimed is:—

1. A musical instrument for producing compound tones the upper partials of which are all in the same temperament as the first partials or primes, said instrument comprising means substantially such as shown and described, for separately generating individual pulsations of simple sine-wave form and equal temperament; and means for selecting and combining into a composite tone of desired quality any of the pulsations so produced. 10

2. A musical instrument for producing compound tones with primes or first partials and upper partials in equal temperament, the same comprising, in combination: means for separately generating individual pulsations of simple sine-wave form and equal temperament; means for selecting desired pulsations; and means for combining the selected pulsations into tones of the desired pitch and quality. 20

3. In a musical instrument, means for producing compound tones the upper partials of which tones are all in the same temperament as the first partials or primes of said tones, and including means whereby each compound tone is 25 produced through the impress upon the air of sets of repetitive impulses of different frequencies as between sets, each said set and frequency being individually generated and of sensibly simple wave-form. 30

4. In a musical instrument, means for producing compound tones, the upper partials of said tones being all in the same temperament as the first partial or prime, and including means whereby each partial of each compound tone is separately 35 produced by the generation of its proper sensibly simple wave-form; and means for synthesizing the component wave-forms into a tone of the desired timbre.

5. In a musical instrument, means for producing a compound tone the upper partials of which are all in the same temperament as the first partial or prime, and including means whereby each partial is produced through individually generated sets of impulses of sensibly 45 simple wave-form; and means for synthesizing all of said partials to produce said compound tones. 40

6. In a musical instrument, means for producing a compound tone of predetermined quality, 50 the upper partials of which are all in the same temperament as the first partial or prime; means for selecting and grading each partial as to relative prominence in accordance with the timbre desired and including means whereby each partial 55 is produced by individually generated sets of repetitive impulses of simple wave-form; and means for synthesizing all of the partials to produce the desired tone quality. 50

7. In a musical instrument, means for producing compound tones, the partials of said tones being all in one temperament, and including means specially designed for individually generating a set of simple, repetitive impulses of predetermined, constant periodicity and sensibly simple wave-form to be used for each and every partial, within the instrument's range, characterized by the said periodicity. 60

8. In a musical instrument, in combination, 70 generators producing pulsations of sensibly simple wave-form and of all of the periodicities of the tones used throughout the instrument, said pulsations being all in the same temperament with respect to each other; manual keys, or 75

equivalent means, for initiating, upon their actuation, the conversion of said pulsations into audible sounds; instrumentalities, under the control of the performer, for predetermining the timbre of the tones to be elicited; switching-means, operable by the finger-keys of the manual and co-operating with said instrumentalities, for selecting and rendering effective, in the case of each key operated, just those periodicities of pulsations necessary to be synthesized for the predetermined tonal result; and means for segregating as to order and regulating as to relative prominence, all the partials simultaneously used, thereby producing at will compound tones of the timbre desired the partials whereof are all sensibly in the one temperament as to periodicity.

9. In a musical instrument, in combination, formed, timed, rotating members and magnetic-flux-varying means associated therewith; pulsation-producing means operated by the flux-variation and serving to convert mechanical motion into sound, each said magnetic-flux-varying means producing sets of repetitious pulsations of sensibly simple wave-form in equal temperament with respect to the others, and thereby generating tones all the components of which are in the same temperament.

10. In a musical instrument, means for generating partial-producing impulses of sensibly simple, sinusoidal wave-form by individual instrumentalities, all said instrumentalities producing in operation sets of repetitious impulses in the same temperament as to periodicity.

11. In a musical instrument, individual instrumentalities adapted to generate partial-impulses of sensibly simple wave-form, all said instrumentalities producing in operation sets of repetitious impulses in the same temperament as to periodicity, and means for selecting, as to their order and relative prominence, the sets of partial impulses to be simultaneously employed.

12. In a musical instrument, in combination, formed, timed, rotating members and magnetic-flux-varying means associated therewith; pulsation-producing means operated by the flux-variation and serving to convert mechanical motion into sound, each said magnetic-flux-varying means being individual to some one periodicity of the instrument and producing pulsations of sensibly simple wave-form in equal temperament with respect to the others, and thereby making possible desired timbres all the components of which are in the same temperament.

13. In a musical instrument, in combination, a plurality of means for generating individual sets of timed, repetitious, partial-producing impulses of sensibly simple wave-form, and of periodicities all of which are in the same temperament; and means for simultaneously employing a plurality of different sets of said repetitious impulses to produce compound tones.

14. In a musical instrument, in combination, a plurality of means for generating individual sets of timed, repetitious, partial-producing impulses of sensibly simple wave-form, and of periodicities all of which are in the same temperament; and means for selecting as to order, grading as to relative prominence, and simultaneously employing a plurality of different sets of said repetitious impulses to produce compound tones.

15. In a musical instrument in which the upper

partials as well as the primes are in the same temperament, and in which the vibrations producing the individual tonal components are of sensibly simple wave-form, means for preventing the intrusion into said components of all impulses which would destroy the simplicity of their wave-form.

16. In a musical instrument in which all the partials are in the same temperament and in which the vibrations producing the individual components are of sensibly simple sinusoidal wave-form, means for restricting these components each to sets of repetitious vibrations of a sensibly simple wave-form and of a periodicity determined by the order of said component and the pitch of the tone of which it is to form a component.

17. In a musical instrument in which all the partials are in the same temperament, a keyboard, and separate means, each responsive to a key of a manual thereof, to produce sets of repetitious impulses of simple wave-form, the periodicities of all of the said sets comprising the periodicities of the primes of an instrument of like gamut when tuned in equal temperament; and means for selecting, grading and simultaneously using desired sets of these impulses in the production of compound tones with all their upper partials as well as their fundamentals or primes, in equal temperament.

18. In a sounder adapted to the bass tones of a musical instrument, a resonant chamber; a vibrating member associated therewith and adapted to set up sonorous waves therein; means for bringing the natural periodicity of said vibrating member into approximate resonance with the note it is intended to serve; and a plurality of means, one or all of which are operable at will, for delivering correctly-timed impulses to said vibrating member.

19. In a sounder adapted to the middle range of a musical instrument, a resonance chamber; a member opposing and near to an opening of said chamber and adapted as it reciprocates, alternately to beat air into and to suck it from the chamber; a spring having an extension by which said member is carried; a magnet core attached to said spring; means for bringing all the moving parts of said sounder into approximate resonance with the pitch of the note it is intended to serve; and rotative means, rendered operable at will, for causing the longitudinal reciprocation of the magnet core, the spring and the member carried by said spring, all in a rhythm adapted to elicit from the resonance chamber a full, fundamental tone of the predetermined pitch desired.

20. In a sounder for a portion of the treble range of a musical instrument, a resonance chamber; a reciprocative member opposing and near to an opening of said chamber; a spring stationary at both ends and supporting said member; a magnet-core supported at the mid-portion of said spring; and means for producing a rhythmical to and fro movement of said core, spring-center and reciprocative member, and thereby causing said member to beat air into and suck it from the resonance chamber and to produce a tone of a pitch characterized by the periodicity of movement of the magnet core.

MELVIN L. SEVERY.
